[57] CLAIM

The ornamental design for a modular still photography studio, as shown and described.

DESCRIPTION

FIG. 1 is a perspective view of the modular still photography studio embodying my new design;

FIG. 2 is a top plan view of the modular still photography studio;

FIG. 3 is a bottom plan view thereof;

FIG. 4 is a front elevational view of the modular still photography studio, the rear view being identical; and,

FIG. 5 is a right-side elevational view of the modular still photography studio, the left-side view being identical thereto.
